UNITED STATES PATENT OFFICE.

CHARLES SMITH, OF PROVIDENCE, RHODE ISLAND.

EASEL FOR FLORISTS' USE.

1,421,595.

Specification of Letters Patent.

Patented July 4, 1922.

Application filed March 11, 1922. Serial No. 543,041.

To all whom it may concern:

Be it known that I, CHARLES SMITH, a citizen of the United States, residing at Providence in the county of Providence and State of Rhode Island, have invented certain new and useful Improvements in Easels for Florists' Use, of which the following is a specification.

The purpose of my present invention hereinafter described is to improve certain features of the patent to me No. 1,407,490, February 21, 1922, in which the rear leg of the easel is, by a screw-eye and nut, clamped in position against beveled grooved lugs projecting laterally from the rear head member, and limited to longitudinal movements for adjustment purposes.

To this end my present invention consists in the provision of means for clamping the rear leg of an easel in position whereby the leg is permitted both longitudinal and lateral movements, and the screw-eye is dispensed with, as are also the beveled lugs.

Referring to the drawings:

Figure 1 is a front elevation of my easel. Figure 2 is a side elevation of the same.

Figure 3 shows a front and edge view of the front head member of the easel.

Figure 4 shows similar views of the rear head member of the easel.

Figure 5 shows a side and an edge view of the rear leg clamping and holding means.

Figure 6 shows one of the easel supporting legs.

Figure 7 shows a sectional and edge view of a member which forms a part of the means for clamping the parts of the easel together, and also as a hinge support for the leg holding member.

Figure 8 is a sectional view showing the hinge supporting member in position in the rear head member of the easel.

Figure 9 is a plan view of the nut forming a part of the clamping means.

Like reference letters and numerals indicate like parts where they occur in the several views.

A represents the easel head composed of two separable members 1 and 2 each having on its inner face oppositely disposed angularly directed grooves located in converging planes, as in my Patent No. 1,407,490, February 21, 1922. The front member 1 is provided with a centrally dis-

posed perforation 1¹, and the rear member 2 is provided with a centrally disposed oblong or rectangular perforation 2¹. Said members 1 and 2 are arranged and adapted to be clamped together with the angularly directed grooves and perforations of one member registering with those of the other member. The two front supporting legs of the easel are placed and held in the grooves of the members 1 and 2 when the latter are joined. (Figs. 1, 2). Said head members 3 are clamped together by a third member 3 one edge of which is straight and abuts against the outer face of the rear head member 2. The outer edge of 3 is angularly inclined relatively to the plane of the inner edge. On the inner edge of the member 3 I provide midway of the length of said edge a rectangular extension 3³, and a laterally extending threaded shank 4. (Fig. 7). fitted for insertion in the perforations of the head members 1 and 2 when the latter are joined, the extension 3³ engaging the rectangular or oblong perforation 2¹ and the shank 4 passing through both the perforations 3³ and 1¹. (Figs. 1, 2, 8). Said member 3 is further provided with a perforation 3⁴ to receive a bolt 9 which serves as a hinge pivot for the holder of the rear leg of the easel. (Figs. 2, 7, 8). Said holder 10 has a tubular body portion open throughout one side with laterally extending wings 10¹, 10², positioned on each side of said opening, and spaced a distance apart laterally and longitudinally. (Figs. 2, 5). The upper wings 10¹ are pierced to receive the hinge pivot bolt 9, and the lower wings are pierced to receive a thumb-screw or a screw 11 which serves to clamp the rear leg 8 of the easel in position in the holder 10. (Figs. 1, 2). The supporting legs of the easel are readily adjustable longitudinally and the rear leg further has capacity to swing on the pivot 9 to vary its angular relation to the front legs of the easel, and to bring it into parallelism with the front legs so the easel may be closed to occupy less room when not in use. Furthermore the rear leg having an oscillating or hinged movement on the member 3 the easel may easily be adjusted to inclined or uneven surfaces. To assemble the parts the front legs are placed in the grooves of one of the head members, the other head member superim-

posed with the grooves and perforation in one of said members registering with those of the other member, the member 3 brought against the rear head member so that the 5 boss 3³ will engage the perforation 2¹ and the shank 4 will pass through the perforations 1¹ and 2¹, and be engaged by the nut 5, to clamp the said parts together. The holder 10 is then secured to the member 3 10 by the hinge pivot bolt 9, the rear leg inserted in the holder 10 and clamped therein by the screw 11. The rectangular boss 3³ in engagement with the corresponding perforation 2¹ of the rear head member serves 15 to prevent sidewise movement of the member 3 and thereby maintains the rear leg of the easel in proper position for service.

The perforation 2¹ may be of the outline of a key-hole or other form so long as it 20 serves the intended purpose of receiving a like projection on the inner edge of the member 3 to prevent the latter from turning or twisting.

I claim as my invention and desire to 25 secure by Letters Patent:

1. In an easel having a head composed of two separable members each provided on its inner face with angularly directed 30 grooves located in converging planes, and with a centrally disposed perforation, and supporting legs held in said grooves, the combination with said parts of a member provided on its inner face with a lateral extension and a laterally extending threaded 35 shank engaging said perforations and a nut engaging said threaded shank whereby said head members and supporting legs are firmly clamped together.

2. In an easel having a head composed of 40 two separable members, one member having a centrally disposed oblong or rectangular perforation, and the other member having a centrally located perforation registering with the rectangular perforation when the 45 two head members are joined, the combination therewith of means for clamping said head members together, the same consisting of a member provided on its inner edge with a rectangular extension corresponding to the perforation in one of said head members, and a laterally extending threaded shank on said inner edge extending through the 50 perforations in said head members, and a nut engaging said threaded shank.

3. In an easel having a head composed of 55 two separable members each provided with centrally disposed perforations registering with each other when said head members are joined, two supporting legs held between said head members and a clamping member arranged to clamp said head members and supporting legs together, the combination with said clamping member of a holder for a third supporting leg of an easel, said holder 60 hinged upon said clamping member and

provided with means for clamping said third easel leg in position in said holder, whereby the angular relation of said third leg to the first mentioned legs may be varied at will.

4. In an easel having a head composed of 70 two separable members each provided with a centrally disposed perforation, said perforations registering with each other when the head members are joined, the combination with said parts of a clamping member 75 consisting of an integral body pierced at its lower portion and having at its inner edge a lateral extension and a laterally extending threaded shank, said extension and said shank engaging said perforations in the head 80 members when the latter are joined, a nut engaging said threaded shank, and a bolt engaging said pierced lower portion of said clamping body to thereby serve as a hinge support for one leg of the easel.

5. In an easel the combination of a clamping member pierced in its lower portion and having at its inner edge a lateral extension and a laterally directed threaded shank, a nut engaging said shank, a holder for one 90 leg of the easel the same consisting of a tubular body open at one side throughout its length, and having laterally extending wings disposed on each side of said opening and spaced a distance apart laterally and longitudinally, said wings pierced, a bolt engaging the pierced upper wings of the holder and the pierced lower portion of the clamping member to thereby form a hinge pivot, an easel leg held in said holder and means 95 engaging said pierced lower wings to thereby clamp said holder upon said leg.

6. In an easel having a head composed of two separable members each provided with centrally disposed perforations registering with each other when the head members are joined, the combination with said parts of the described clamping member the same consisting of a body portion having one inner straight edge and an opposite edge 110 angularly inclined relatively to said first edge, a lateral extension and a laterally extending threaded shank both disposed on said straight edge, a nut engaging said threaded shank, said lateral extension and threaded shank engaging the perforations in said head members when the latter are joined, and said body portion of the clamping member pierced in its lower portion to receive a pivot bolt, with the described 115 holder for the rear leg of an easel the same consisting of a tubular body portion open on one side throughout its length and having laterally directed wings located on each side of said opening and spaced a distance apart 120 laterally and longitudinally, the upper wings pierced to receive a hinge pivot bolt engaging the pierced lower portion of the body of the clamping member, and the lower wings pierced to receive a screw whereby 125 130

said holder is clamped upon the rear supporting leg of an easel.

7. The described holder for the rear leg of an easel, the same consisting of a tubular body portion open on one side throughout its length, and provided with laterally directed wings located on each side of said

opening and spaced a distance apart laterally and longitudinally, the upper wings pierced to receive a hinge pivot bolt and 10 the lower wings pierced to receive a screw whereby said body portion is clamped upon the supporting leg of an easel.

CHARLES SMITH.
